ATTORNEYS.

UNITED STATES PATENT OFFICE.

WILLIAM A. TEBO, OF ANTHONY, RHODE ISLAND, ASSIGNOR TO DRAPER CORPORATION, OF HOPEDALE, MASSACHUSETTS, A CORPORATION OF MAINE.

SHUTTLE.

Application filed June 2, 1925. Serial No. 34,389.

This invention relates to an improvement in shuttles more particularly an improved construction of yarn guide eye through which the yarn from the shuttle package 5 is drawn; and the object of this invention is to mount an eye in the shuttle with a cushioning material between the eye and its surrounding walls.

A further object of this invention is to 10 support an infrangible guide eye having a longitudinal or axially-disposed threading opening in the shuttle such that the same may be readily positioned and securely held and at the same time cushion the eye to 15 prevent its being broken from the impact of the shuttle with its check in the loom.

A still further object of this invention is the provision of means to prevent the thread from being caught between the eye 20 and the bushing in which the same may be mounted.

With these and other objects in view, the invention consists of certain novel features of construction, as will be more fully described, and particularly pointed out in the appended claims.

In the accompanying drawings,

Figure 1 is a plan view of a portion of a shuttle broken away and showing in section the eye through which the yarn is drawn.

Figure 2 is a side elevation of the same.

Figure 3 is a perspective view of a metallic bushing of the type used in automatic 35 shuttles.

Figure 4 is a perspective view of a porcelain guide eye for insertion into the bushing.

Figure 5 is a sectional elevation showing 40 the porcelain eye mounted in the bushing with the fingers of the bushing folded into notches in the guide eye.

Figure 6 is a perspective view illustrating one means of inserting an eye in the bushing by incasing the same in a tubular elastic member.

Figure 7 is a fragmental plan view of a hand-threading shuttle partly in section showing a porcelain eye as mounted in the 50 shuttle by means of an elastic member.

Figure 8 is a side elevation of the same.

Figure 9 is a perspective view showing a porcelain guide eye as mounted in the bushing of the type adapted to be threaded into a hand-threading shuttle.

Figure 10 is a side elevation illustrating the elastic member as helically wound in a stretched condition about the porcelain guide eye which may be placed in the shuttle opening.

Figure 11 is a perspective view illustrating a porcelain guide eye with strips of elastic material indicated as placed longitudinally thereof.

It is found in the practical operation of 65 shuttles for weaving, of advantage to employ a porcelain bushing in the eye thereof through which the yarn is drawn, owing to the well known fact that the wearing life of an eye formed of this infrangible 70 porcelain material is more than double that of any other material that can be used for this purpose and is practically that of the shuttle itself as it will not score or groove by action of the yarn running therethrough. 75

In automatic shuttles where the tubular eye must be split along its side to permit the threading of the yarn therethrough, it has heretofore been found to be impractical to use a porcelain eye therein owing to the 80 fact that the impact of the shuttle in being checked in its flight when driven back and forth across the loom soon cracks or breaks this fragile porcelain eye to such an extent as to render its use impractical in this style 85 of shuttle. Therefore, to obviate this very serious difficulty, I have positioned a cushioning layer of flexible material such as rubber or other suitable yieldable material between the eye and the walls of the opening in which the eye is set, which material serves to absorb the shocks and so effectively prevent the porcelain eye from being injured by these shocks to which it is subjected thereby prolonging its working life 90 to substantially that of the shuttle itself. 95

Further, at the time of the insertion of the eye into the shuttle opening the rubber or yieldable material is placed under tension to reduce the thickness of its surrounding walls after which this elastic material is released from this tension to permit it 100

- to thicken and be compressed and so yieldingly bind the walls of the eye in the walls of the opening to grip and so secure the eye in the opening without other fastening.
- 5 It is further found desirable to provide fingers cut from the stock of the bushing to be bent inwardly into notches in the yarn guide eye to assist in holding the eye in its position in the bushing and also to form a
- 10 guide to prevent the thread from catching between the eye and the walls of bushing; and the following is a detailed description of the structure embodying my present invention:—
- 15 With reference to the drawings, 10 designates an automatic shuttle which may be formed of any suitable material and which is provided with an automatic threading member 11 and a yarn package 12. In the
- 20 forward end of this shuttle there is mounted in a recess 13 a bushing 14 of metal or any suitable material which is substantially circular in form and provided with a narrow threading neck 15 through which the yarn
- 25 enters in the threading operation, and in order to prevent the yarn from grooving or scoring the bushing, I have mounted a guide eye 16 in this bushing by tensioning an elastic material 17 during the positioning of the
- 30 eye in the bushing whereby the thickness of the walls of the elastic material is reduced and then the elastic material is released to expand and bind the eye in the bushing. This elastic material may be in the form of a
- 35 tube 18, stretched and drawn through the eye-receiving opening, as illustrated in Figure 6, or it may be wound helically about the eye as at 19 in Figure 10, or it may be used in the form of longitudinal strips 20, preferably a plurality, as illustrated in Figure
- 40 11, or the elastic material may be in any other desired form, the elastic material in the first two cases being suitably cut away or severed to permit contraction of the elastic
- 45 material to leave the threading opening 21 of the guide eye free for the threading of the yarn thereinto. It will be apparent that the elastic material will not only expand to bind the eye in its position but will also
- 50 form a cushion for the eye to prevent its breaking upon the shuttle being checked in its flight. In order to more effectively secure the eye in its position in the bushing the eye may be recessed or notched as at 22
- 55 and into these recesses fingers 23 cut from the stock of the bushing are rolled or folded as at 24, the ends of these fingers being doubled under to protect them from engagement with the yarn.
- 60 In some instances, as shown in Figures 7 and 8, the porcelain member 25 is cast in the desired form having a slit 26 and is positioned directly in the shuttle without the use of a bushing being secured therein by means of an expandible member 27 between the

walls of the eye and the walls of the shuttle opening, in the same manner as mounting the porcelain eye in the metallic bushing.

Figure 9 illustrates a porcelain eye 28 mounted in a metallic bushing 29 by means 70 of rubber or other suitable expandible material 30 the same being then adapted to be positioned in the hand-threading shuttle or the like in the usual manner.

It will be readily apparent from the above 75 that I have provided a simple and practical means of inserting an eye of infractible material into a shuttle, by which construction the eye of infractible material is securely held in position and is cushioned 80 against breakage due to the impact of the shuttle in being operated in a loom.

The foregoing description is directed solely towards the construction illustrated, but I desire it to be understood that I reserve the privilege of resorting to all the mechanical changes to which the device is susceptible, the invention being defined and limited only by the terms of the appended 85 claims.

I claim:

1. In a textile device having an opening therein, a yarn guide eye of infractible material in said opening and compressed elastic material between the walls of said eye and the wall of said opening securing the eye in the opening by the expanding action of said elastic material.

2. In a textile device having an opening 100 therein, a yarn guide eye of infractible material having a covering of compressed elastic material and secured in said opening by the expanding action of said covering.

3. In a shuttle having an opening for the delivery of yarn therefrom, a porcelain yarn guide for protecting the material of the shuttle, compressed elastic material between the guide and the shuttle body to retain the guide in position by the extending action of said material.

4. In a shuttle having an opening for the delivery of yarn therefrom, a yarn guide of infractible material having a curved yarn engaging surface and mounted in the shuttle body, and an elastic material between the yarn guide and shuttle body to secure the yarn guide in position by the expanding action of the elastic material.

5. In a shuttle having an opening for a 115 yarn guide eye, a guide eye of infractible material therein and an elastic rubber covering for said eye between the eye and the walls of said opening to cushion and secure the eye in its opening by the expanding action of the covering.

6. In a shuttle having an opening through which the yarn is led therefrom and a slit leading to the opening for the threading of the yarn, a yarn guide eye in said opening having a cooperating threading slit for re- 120

- ceiving the yarn and elastic rubber material between the walls of said eye and the wall of said opening for securing the eye in said opening by the expanding action of the elastic rubber material.
7. In a shuttle, a bushing having a longitudinal thread receiving opening through one wall thereof, a yarn guide eye of inflexible material in said bushing having a longitudinal slot therein and a bendable member in said bushing engaging said eye to lock the eye in the bushing.
8. In an automatic shuttle, a bushing having a threading opening, a yarn guide eye in said bushing having a corresponding threading opening, and means for preventing the thread from catching between said bushing and yarn guide eye.
9. In a shuttle, a bushing having a longitudinal thread receiving opening through one wall thereof, a yarn guide eye of inflexible material in said bushing having a longitudinal slot therein with notches in the side walls of said slot and fingers attached to the bushing adjacent the thread-receiving opening and bent into said notches to prevent the thread from catching between the bushing and guide eye.
10. In an automatic shuttle, a bushing having a threading opening, a yarn guide eye in said bushing having a corresponding threading opening with notches in its side walls and fingers cut from the stock of said bushing and folded into said notches.
11. In an automatic shuttle, a bushing having a threading opening, a yarn guide eye in said bushing having a corresponding threading opening with notches in its side walls and fingers cut from the stock of said bushing and folded into said notches, the ends of said fingers being doubled under to prevent the ends of the fingers contacting with the yarn.

In testimony whereof I affix my signature.

WILLIAM A. TEBO.
